UNITED STATES PATENT OFFICE.

EDWARD SCHWARTZ, OF CHICAGO, ILLINOIS, ASSIGNOR TO PELOUZE MANUFACTURING CO., OF CHICAGO, ILLINOIS.

DESIGN FOR A SCALE.

42,861.

Specification for Design.

Patented Aug. 6, 1912.

Application filed February 24, 1912. Serial No. 679,628. Term of patent 14 years.

To all whom it may concern:

Be it known that I, EDWARD SCHWARTZ, a citizen of the United States of America, and a resident of Chicago, in the county of Cook and State of Illinois, have invented a new, original, and ornamental Design for Scales, of which the following is a specification, reference being had to the accompanying drawing, forming part thereof.

Figures 1 and 2 of the drawing are front

and side elevations respectively of a scale showing my new design.

I claim:

The ornamental design for a scale, as shown.

EDWARD SCHWARTZ.
